UNITED STATES PATENT OFFICE

2,501,380

LIFTING APPARATUS

Oscar E. Dempsey, Tulsa, Okla., assignor to
 Dempsey Pump Co., Tulsa, Okla., a corporation
 of Oklahoma

Application August 12, 1946, Serial No. 690,006

10 Claims. (Cl. 103—46)

1

This invention relates to improvements in an apparatus for flowing wells, and more particularly, but not by way of limitation in a lifting means to maintain a substantially continuous flow of well fluid in the production strata without interference from the lifting medium. This invention is an improvement on applicant's Patent No. 2,396,162, dated March 5, 1946, as well as applicant's co-pending application Serial Number 645,305, filed February 4, 1946, which matured into Patent No. 2,469,225, issued May 3, 1949.

In applicant's previous patent and co-pending application the supply pressure fluid was allowed to leak past a top valve to cause movement downward of a plurality of slide valves assisted by the tension of a spring in order to release mechanical latching means whereby the top valve would be moved into a position to permit direct thrust of the supply pressure fluid into a displacement chamber. The present invention utilizes a substantially lesser number of working parts, particularly omitting the mechanical latching means and tension spring to provide a more exact apparatus by the use of a positive acting valve unit directly influenced by motive pressure fluid or exhaust residue fluid to move it from open or closed position in order that the production liquid may be displaced and the residue motive fluid exhausted therefrom. In addition to the more positive functioning of the automatic valve unit, the present invention utilizes a piston valve providing a retarding or snubbing action in a manner similar to applicant's co-pending application above referred to.

It is, therefore, an important object of this invention to provide a lifting unit for the displacement of fluid from a well which progressively lifts quantities of the fluid from a lower collection chamber to a reservoir disposed at a higher level, said lifting unit having a valve mechanism for controlling the discharge of supply pressure fluid into the lower chamber wherein a portion of the displaced fluid acts as a snubber to maintain said valve mechanism in an open position for the discharge of the input pressure fluid until substantially all of the production fluid from the lower chamber is displaced.

And still another object of this invention is to provide a lifting unit for displacing oil from the well by progressively lifting quantities of fluid from a lower collection chamber to a reservoir disposed at a higher level, said lifting unit having a valve mechanism controlling the input of supply pressure fluid into the lower chamber for displacing the fluid as well as the control of the

2

exhaust of the residue supply fluid after displacement of the fluid from the lower chamber, said mechanism providing for a positive bleed down to an exact minimum of the residue pressure fluid which is undisturbed by any valve leakage or sand deposits or abrasions in the mechanism.

And still another object of this invention is to provide a lifting unit for displacing oil from the well by progressively lifting quantities of fluid from a lower collection chamber to a reservoir disposed at a higher elevation, said lifting unit having a valve mechanism controlling the input of supply pressure fluid to provide sufficient time to increase the supply pressure fluid necessary for the displacement of the well fluid from the lower collection chamber prior to shutting off the incoming pressure fluid and thereafter allowing for an exhaust of residue pressure fluid.

And still another object of this invention is to provide a lifting unit for displacing fluid from a well which is readily adaptable to widely divergent ranges of bottom hole pressure, thereby providing a unit equally capable of operating in stripper wells having a low bottom hole pressure, or wells having a high sand pressure without dissipating the oil sand to the intrusion of water.

Another noteworthy object of this invention is to provide an automatic fluid actuated lifting unit for wells which readily adapts itself to a variable and fluctuating actuating fluid pressure wherein the operation of the unloading element is contingent upon a relationship of percentages of the actuating fluid pressure to a build up or an accumulated pressure in a storage chamber.

And an additional object of this invention is to provide an automatic fluid actuated lifting unit for wells which is adapted for a continued operation irrespective of a complete or partial replacement of the production fluid from the production strata, said unit providing a rate of production fluid displacement exceeding the maximum rate of production fluid entering the well bore without seriously affecting the working parts so that the well may be continuously produced at a bottom hole pressure substantially sufficient to maintain a fluid level in proximity of the unit.

And an additional object of this invention is the economic use of small volumes of gas in cubic feet for progressively lifting small amounts of fluid into a reservoir to be intermittently slugged in predetermined quantities, thereby eliminating the use of large volumes of gas to

slug small amounts of entrapped oil all the way through the tubing string.

Other objects and advantages of the invention will be evident from the following detailed description read in conjunction with the accompanying drawings which illustrate my invention.

In the drawings:

Figure 1 is a sectional elevational view of the well bore showing a portion of the lifting unit in elevation disposed therein.

Figure 2 is a similar view showing the remaining portion of the lifting unit.

Figures 3 and 4 are fragmentary sectional elevational views of the lifting unit per se showing one operating position of the valves.

Figures 5 and 6 are fragmentary sectional elevational views in schematic arrangement showing another position of the valves.

Figures 7 and 8 are views similar to Figures 5 and 6 showing the valve mechanism in still another position.

Figures 9 and 10 are similar views and showing the valve mechanism in still another position of operation.

Figures 11 and 12 are views similar to Figures 9 and 13 showing the valve mechanism in another position of operation.

Figure 13 is a sectional view taken on lines 11-11 of Figure 3.

Figure 14 is a sectional view taken on lines 12-12 of Figure 1.

Figure 15 is a sectional view taken on line 13-13 of Figure 1.

Referring to the drawings in detail and more particularly Figures 1 and 2, reference character 2 represents the well casing extending from the surface of the well to the producing strata thereof. A string of well tubing 3 is disposed in spaced relation within the casing 2. A lifting unit 4 is suspended on the tubing 3 on a string of "macaroni" tubing 5 of reduced diameter. The lowermost section of the tubing 3 in proximity of the production strata is specially formed to include inwardly projecting shoulders 6 for supporting a flange portion 7 of the unit 4 when inserted in the tubing 3. It will be apparent that the shoulders 6 also support the tubing 5 extending to the surface of the well. The lower end of the unit 4 is provided with packing rings 8 for anchoring the unit in a reduced nipple 9 of the tubing 3. A gas anchor 10 having a plurality of perforations or apertures 11 is secured to the tubing 3 in spaced relation thereto at a point below the casing 2.

Referring to Figures 3 and 4 the lifting unit 4 comprises a cylindrical housing 12 adapted at its upper end to receive the valve unit 13 and a manifold at its lower end. Housing 12 has a bore 15 of varying diameters in which is disposed the main valve unit 14. The upper portion 16 of bore 15 receives a cross-over plate 17 provided with a radially bored passageway 18 communicating with a vertical bore 19 on its upper face to receive an extension 20 of a cylindrical member 21 hereinafter to be referred to. The lower portion of bore 15 receives valve seat plate 22, and cylindrical members 23 and 24. The main valve unit 14 is adapted to cooperate with lower piston unit 62.

Referring to Figures 3 to 10, inclusive, supply pressure fluid is constantly maintained in the tubing 5, in direct communication with a passageway 26 provided in the unit 4. The input duct 26 is composed of aligned passageways through members 21, 28, 17 and 12, and com-

municates with bore 15 in which is disposed the upper portion of main valve unit 14. The main valve unit 14 comprises an outer cylindrical sleeve 29, having lower tapered valve member 31 secured thereto. The outer periphery of the sleeve 29 is provided with conventional sealing or packing members 32 effectively sealing off the upper portion of bore 15 from direct communication with passageway 26. This upper portion 10 of bore 15 above the valve sleeve 29 provides a chamber 33. A cylindrically-shaped pilot valve 34 having a bore 35 therein is slidable within the sleeve 29. The sleeve 29 is provided with a plurality of circumferentially-spaced apertures 36 in communication with the input passageway 26. The lower portion of main valve 14 is adapted to operate in a bore 37 of the cylinder 23 and engage the tapered seat 38 of the plate 22 as will hereinafter be referred to. The bore 35 of pilot valve 34 communicates with an aperture 39 therein and a bore 40 of valve 31, and bore 41 of cylinder 24 and into cavity 42 of member 24 in which is located the pilot valve tripping device adapted to cooperate with main valve 14.

With the valve 14 shown in its open or input position (Fig. 3) the supply pressure fluid discharges from passageway 26 into bore 15 and hence through the apertures 36 into the chamber 33 and through the apertured plug 43 secured to the pilot valve 34 to discharge into the chamber 35 below the plug. A spherically-shaped valve 47 is positioned within the chamber 35 and cooperates with the aperture 39 provided in the pilot valve. The aperture 39 has tapered portions 46 acting as a seat for the spherically-shaped ball valve 47. The valve sleeve 29 is disposed in spaced relation to the inner periphery of the bore 15 to provide a lower chamber 48, in direct communication with supply pressure fluid 40 which simultaneously flows through port 49 in plate 22 and into bore 37 and passageway 50 in communication with the chamber 42 provided by the cylindrical member 24 arranged in spaced relation to housing 12. The lowermost portion 45 of cavity 42 is of reduced diameter provided by a recess in the upper end of manifold 51 from which a passageway 52 extends downwardly therethrough. The lower end of manifold 51 is secured to tubular member 53 and is provided 50 with a counterbored recess 54 for receiving the cylindrical member 55 disposed in spaced relation to the central bore 56 of manifold 51. The lower ends of members 53 and 55 are secured by tight-fitting collar 57 having an aperture 58.

Passageway 52 communicates with the annulus 59 formed by members 53 and 55 and supply pressure fluid flowing therethrough has an outlet port 60 provided in collar 57. Thus the lower portion of chamber 61 provided by cylinder 55 is in direct communication with input passageways 50 and 52 as well as chamber 42.

The chamber 61 contains the piston unit 62 which is similar in structure to that disclosed in applicant's co-pending application Serial No. 645,305 heretofore mentioned. A perforated tube 63 extends downwardly from collar 57. A cage member 64 having a ball valve 65 is provided at the lower end of tube 63. The packing rings 8 surround the outer periphery of the cage 64 and are adapted to anchor the lowermost end of the unit 4 in the reduced nipple 9, as shown in Figure 2. The chamber 61 housing the piston unit 62 which comprises a cylindrical piston 67 having a flange 68 provided on the outer periphery thereof. A plurality of rings and cups 70 bear

against the inner periphery of the cylinder 55, with the cylinder 67 arranged in spaced relation thereto. The upper end of the cylinder 67 is provided with apertures 69 for a purpose as will be hereinafter set forth. The lower portion 71 of the cylinder 67 extends through the aperture 58 in the collar 57, so that a portion of the cylinder 67 is substantially disposed within the confines of the tube 63. A valve cage 72 is secured to the lower end of cylinder 67 and contains a ball valve 73 for a purpose as will be hereinafter set forth. The tube 63 is provided with a plurality of vertically-spaced apertures 74 (Figure 2) providing communication between the interior 75 and a chamber 76 formed between the cylinder 63 and tubing 3. It will be apparent that the apertures 74 will equalize fluid pressures and levels therebetween. Packing rings 78 are disposed on the outer periphery of the manifold 51 and contact the projection 6 of the tubing 3, as shown in Figure 1.

Operation

The static level of the well fluid standing adjacent to the gas anchor apertures 11, constitutes the sand pressure of the well and will permit flow of fluid from the production strata through the ball valve 65 into the displacement chamber 76 whenever the residue of supply fluid pressure remaining in chamber 76 from a previous cycle of the main valve member 14 is sufficiently decreased below that of the static pressure. As heretofore mentioned motive pressure fluid is constantly maintained in the passageway 26 from a surface compressor or like equipment (not shown) and with the valve in open position, as shown by Figures 3 to 6 is discharged through passageways 50 and 52 into the chamber 61 beneath the piston flange 68 thereby causing movement of the piston unit 62 vertically upward. Movement of the piston unit 62 partially moves the upper cylinder 67 into the longitudinal bore 56 provided in member 51. The bore 56 communicates with an annulus or reservoir 80 provided between the tubing 3 and 5 (Figure 1) through an outlet port 81 provided in member 51. However, upward vertical movement of the piston unit 62 is limited or retarded due to previously displaced well liquid or fluid that is normally present in chamber 61 above the flange 68.

Movement of the piston unit 62 vertically upward is due to a pressure differential between the upper part of chamber 61 above the flange 68 and the lower portion thereof, below the flange 68. The upward movement of the piston unit 62 is retarded or arrested because the piston unit 62 moves upward against the volume of previously displaced well liquid or fluid that is present in the chamber 61 and bore 56 above the flange. As the piston unit moves upward in chamber 61 the snubbing action provides an element of time which enables the motive pressure fluid flowing from the chamber 61 below the flange and through the port 58 and into the displacement chambers 76 to build up the pressure in the displacement chamber sufficiently to overcome the static pressure of the liquid above the ball valve 73 thereby causing displacement or movement of the production liquid from the chamber 76.

As supply pressure fluid discharges through port 58 into the displacement chamber it will build up or increase the pressure therein sufficient to cause displacement of the production liquid in the chamber 76 and discharge through

the ball valve 73, simultaneously causing movement of the liquid in the chamber 82 between the ball valve 73 and the outlet port 81. The arresting of the piston unit 62 will be maintained during the displacement of liquid from the chamber 76, because the volume of liquid flow through outlet port 81 is less than the volume of supply fluid capable of flowing through the port 58 due to the characteristic differences of liquid versus gas flow. Therefore the volume of supply pressure fluid through port 58 will maintain a pressure condition in displacement chamber 76, bores 56 and 82 greater than the static pressure condition upstream from outlet port 81, as long as liquid commands port 81. This pressure in 76, 56 and 82 will closely approximate pressure of gas in lower portion of 61 and thus obviously in upper part of 61. Continued displacement of the liquid from chamber 76 and through ball valve 73 and outlet port 81 moves substantially all of the liquid through the outlet port 81 thus uncovering port 84 to cause discharge of the motive pressure fluid through the ball valve 73, bore 56 and through the port 81.

It will be apparent that the difference in area of outlet port 81 and port 58 will allow the motive pressure fluid to discharge through port 81 at a much greater volume than the motive pressure fluid flowing through port 58, therefore the pressure condition in bore 56 and the upper portion of chamber 61 is decreased. The decreased pressure condition in bore 56 allows previously displaced production liquid standing in chamber 61 above the flange 68 to be displaced into bore 56, by the motive pressure fluid acting against the underside of flange 68 to move the piston unit 62 vertically upward to the top of the chamber 61 (Figure 8) and fluid through the port 81 completing the movement of piston unit 62.

It will be apparent that the retarded position of piston 62 will remain substantially stationary during the displacement of production fluid entrapped in chamber 76 however the snubbing action of the piston unit 62 is only necessary for the time required for the volume of supply pressure fluid flowing through port 58 to be increased, and provide a greater pressure in chamber 76 than the static pressure of liquid commanding port 81 irrespective of the static pressure condition at port 81 under any condition. From the foregoing, it will be obvious that time interval will be variable depending upon the variable pressure conditions that may be present or may command port 81.

The completed upward travel of the piston unit 62 (Figure 8) causes the cage 85 of cylinder 67 to contact a valve trip rod 86 extending from chamber 42 through an aperture 87 in member 51 and into the bore 56. An extension 88 of reduced diameter is secured to the lower end of trip rod 86 and extends through the apertured cage 85 into the chamber 82 of the cylinder 67. An enlarged projection 89 is provided at the end of extension 88 in order to maintain it within the cylinder 67. The contact of the top part 85 of cylinder 67 with the trip rod 86 moves an upper flange 90 into contact with a flange 91 provided on an extension rod 92 secured to spherical-shaped valve 47. The rod 92 extends through the aperture 39, bore 40 and 41 and into the chamber 42 in which is disposed the flange 91. Movement of the rod 86 also moves rod 92 vertically upward to remove the valve 47 from its tapered seat 46 and hence vertically up-

ward into contact with the apertured plug 43. This will provide vertical upward movement of the pilot valve 34 in the sleeve 29 past the plurality of apertures 36, thereby closing off chamber 33 from the input of pressure fluid in passageway 26. With the valve 47 in unseated condition as shown in Figures 5 and 7 the volume of fluid pressure in chamber 33 discharges through apertures 93 in plug 43 through aperture 39, bore 40 and a small leak-port 95 in cylinder 24 providing communication between bore 40 and an exhaust passageway 96. The exhaust passageway extends from communication with port 18 by a drilled aperture 97 in inwardly projecting shoulder 98 of cylinder 12, and aligned apertures 99, 100 and 101 in members 22, 23 and 24, respectively. The tubing 3 (Figure 1) is provided with a plurality of circumferentially spaced apertures 103 providing communication between port 102 in manifold 51 and an annulus 104 provided between tubing 3 and casing 2.

Movement of the rod 86 upwardly contacts and moves the flange plate 91 upwardly into an effective contact with faced end 105 of bore 42. The tapered valve member 31 is provided with a faced end 106 contacting a portion of the upper end of cylinder 24 exposed to bore 37 of cylinder 23. Therefore, with the valve positions as shown in Figure 5, the leak port 95 is in direct communication with the volume of supply pressure fluid contained in bore 41 and 40, aperture 39 and chamber 33. The reduced pressure in chamber 33 permits the thrust of input supply pressure constantly maintained in chamber 48 to move the main valve unit 14 upwardly to a position which brings the tapered shoulders 107 of valve 31 into seating position with tapered portion 38 of plate 22 as shown in Figures 3 and 7. This movement closes off passageway 50 from communication with passageway 26 and the flow of supply pressure fluid therefrom, and further opens passageway 50 to a modulated or restricted communication with the lower or exhaust pressure area now present in bore 37 of cylinder 23 directly communicating with the full area of discharge passageway 96. The upward movement of valve unit 14 and particularly of sleeve 29 alters the relative position of the pilot valve 34 with the apertures 36 as will be hereinafter referred to. An apertured thimble 109 secured to cross-over plate 16 cooperates with the movement of sleeve 29 to regulate the positioning of valve 34 and may be so arranged as to substantially move the apertured plug 43 out of contact with valve 47. It will be understood that the relationship of pressures is commensurate with the areas of the various valves, pistons and bores and the ratio between them is a matter of choice depending upon a particular unit.

With the valve unit 4 in the position, as shown in Figure 7, the residue pressure fluid present in the displacement chamber 76 and chamber 61 below the flange 68, passageway 59, chamber 42 and passageway 50 is allowed to exhaust around the reduced outer periphery 110 of the lower body portion of valve member 31, and into the exhaust passageway 96. The exhaust of supply pressure fluid from the displacement chamber and input passageways, relieves pressure against valve 73 and permits the oil or production fluid that has been displaced to the annulus 80 to move the piston unit 62 vertically downward to a position as shown in Figure 10. Downward movement of piston unit 62 also moves rod 86 and upper flange 98 downward due to cage 85 of cylinder 67 contacting rod flange 89.

The flange 91 will remain seated against the face 105 of cylinder 24 until the pressure of the residue supply fluid present in chamber 42 bleeds off sufficiently to no longer hold the weight of flange 91, rod 92 and valve 47 firmly against the face 105. It is understood that the low pressure area formed above plate 91, when firmly seated against face 105 permits the higher pressure in chamber 42 to maintain the combined weight of the flange, rod and valve thereagainst. The escaping exhaust pressure flowing from cavity 42 and passageway 50 into the bore 37 must pass by the reduced portion 110 of valve 31, and through a port 111 communicating with exhaust passageway 96. The bleeding down of residue pressure fluid provides a pressure in chamber 37 substantially equal to the bottom hole pressure in annulus 104. From the foregoing it will be apparent that the flange 91 is maintained against its seat 105 until substantially all residue pressure fluid is exhausted thereby permitting flow of production fluid through valve 65 under influence of the sand pressure.

In this condition as shown in Figure 9, supply pressure fluid present at apertures 36 is allowed to leak around the outer periphery of the pilot valve 34 and a reduced portion 112 into the chamber 33. The leakage of motive pressure fluid is permitted by the loose fit of the pilot valve 34 with its bore, the inner periphery 113 of the sleeve 29. Leakage of supply pressure fluid into the chamber 33 builds up a pressure condition therein to force the pilot valve 34 downward and thereby open apertures 36, whereby chamber 33 is subject to the full pressure of the supply fluid to cause vertical downward movement of the valve unit 14, as clearly shown in Figure 3, thereby moving valve section 31 downward to open port 49 allowing discharge of supply pressure fluid into the passageway 50 and 52 and port 58, so that the operation against the piston unit 62 and displacement chamber 76 is repeated.

The foregoing has been concerned mainly with the action of the main valve unit 14 and piston unit 62 for the displacement of liquid entrapped in the chamber 76 to a reservoir or storage chamber 80 located at a higher elevation. It will be apparent from the description, supra, that the operation of the main valve 14 re-occurs without regard to or the presence of oil existing in the displacement chambers 76. During the cycles of operation in which the main valve operates without any oil, or sufficient oil in the displacement chamber to warrant the presence of sufficient oil above the valve 73 in chamber 76, it will be obvious that the piston unit 62 is capable of moving through its complete cycle uninterrupted by the flow of entrapped oil flowing in chambers 82 and 56. This condition will obviously cause a more expeditious function of the flange 91 and its valve 47 to close off the input ports 36 through an upward movement of the pilot valve 34.

The oil displaced to the reservoir 80 builds up a hydrostatic head of pressure therein acting against the upper differential valve unit 13 previously referred to.

Referring to Figures 1 and 3 the valve unit 13 comprises the upper housing member 21 interconnected between the housing 12 and the upper plug 27 in turn connected with the "macaroni" tubing 5, as shown in Figure 1. The cylindrical member 21 is provided with a valve manifold 23 having a bore 115 communicating with aligned

bore 116 and 117 in cylinder 21 to provide a housing for the valve unit 13. The unit 13 comprises an upper piston 118 secured to a shaft 119 extending downwardly therefrom. The outer periphery of the piston 118 is provided with a plurality of packing cups 120 adapted to contact the inner periphery of the bore 115 for a purpose as will be hereinafter described. The lower portion of shaft 119 is of increased diameter as at 121 providing tapered portions 122 adapted to cooperate with a tapered aperture 123 provided in the manifold 28. The valve portion 121 is provided with a recess or socket 124 for receiving a ball projection 125 of a sliding valve 126 extending downwardly therefrom into the bores 116 and 117. The plug 21 is formed with a passageway 127 providing communication with the reservoir or annulus 80 and the bore 115 above the piston 118. The member 21 is similarly formed with a port 130 providing communication with the reservoir 80 and the bore 116 for a purpose as will be hereinafter set forth. The constantly maintained motive pressure fluid is directed from the "macaroni" tubing 5 downward into a passageway 131 in plug 21 into communication with an annulus 132 which in turn communicates with a passageway 133 provided in the manifold 28 to direct supply pressure fluid from the tubing 5 into the bore 115 beneath the piston 118. With the piston 118 in closed position, as shown by Figures 3 and 7, it will be understood that the piston will remain as such by the presence of supply pressure fluid acting against the lower face thereof, and also influenced by the reservoir pressure in passageway 130 leaking past the loose fit of valve 121 in the bore 116, until the hydrostatic head of displaced production liquid in reservoir 80 acting against the top of piston 118 through passageway 127 is sufficient to overcome the upward thrust thereagainst. The bore 117 is in communication with the exhaust passageway 96 as clearly shown in Figure 3 and as a consequence there may be a negligent pressure existing against the underface of valve 126 from the exhaust passageway 96. It will be apparent that if there is any exhaust or casing pressure in passageway 96, the reservoir pressure acting against the top of piston 118 must be sufficient to overcome this pressure as well as the effective area of supply pressure fluid in existence in bore 115 below the piston 118.

The ratio of the area between the bore 115, the effective seating area of the tapered valve 121 at its tapered seat 123, and the perfect seal created by the lower piston valve 126 in its bore establishes the percentage of pressure necessary in the reservoir 80 to overcome the effective upward thrust of supply pressure fluid existing in chamber 115 below piston 118, and the exhaust pressure acting against the lower valve 121 from the exhaust passageway 130, to move the piston 118 downward along with downward movement of the valves 121 and 126 thereby opening port 130 to the direct discharge of supply pressure fluid from bore 115 and passageway 133 in order to slug the liquid standing in the reservoir 80 to the top of the well.

In order to obtain the percentage of pressure to move piston 118 downward (Figure 5) in relation to the supply pressure fluid, it will be apparent that the area of the piston 118 minus the effective area of the tapered portions 122 of valve 121 multiplied by the pressure maintained in chamber 115 will produce the sum of the upward thrust acting against the lower face of piston 118.

The downward thrust is obtained by the area of piston 118 plus the area of valve 126 minus the effective area of the tapered portion 122 multiplied by the pressure in the reservoir. This is because the reservoir pressure acts upwardly against valve 121, and downwardly against valve 126. Therefore in order to determine the pressure required to move the piston 118 and open the valve 121 away from its tapered seat 122 will be the sum of the areas and pressures obtained from the downward thrust relative to the sum of the areas and pressures obtained by the upward thrust.

It will be apparent that once the flow starts in the annulus 80 that the pressure of the input fluid will also be directed through the passageway 127 and assist in maintaining the piston 118 in downward position (Figure 11) until substantially all of the oil is slugged from the annulus to the top of the well. As soon as the oil is displaced from the annulus 80, a diminished pressured condition exists in the annulus due to the exhausting and expansion of the input fluid therein. This permits the greater pressure in chamber 115 acting against the bottom of the piston 118 and move it to closed position as shown in Figure 3.

It will be apparent that the areas of the various valves and their bores are variable and the relationship therebetween is dependent upon a particular unit and the environment or characteristics of the well with which it is utilized. Both the opening and closing pressure of the valve unit 13 may be varied within a selected range of operating efficiency.

From Figure 1 an apertured screen 140 is shown disposed in the "macaroni" tubing 5 and is employed to keep the incoming motive pressure fluid discharging through the valve unit 14 substantially free from pipe scale and other debris, while the motive pressure fluid entering and discharging to the intermittent valve unit 13 may be taken from a sump 141 surrounding the screen 140.

From the foregoing, it will be apparent that the invention contemplates the intermittent lifting of small quantities of oil from a lower filling chamber to a higher reservoir, and functions in such manner to prevent any supply pressure fluid utilized for displacing the oil from counteracting the sand pressure of the well, so that there is always a constant emission of fluid from the production strata except for the momentary period during the displacement operation. Furthermore, the lifting unit comprises an automatic valve mechanism for controlling the supply pressure fluid into the displacement chamber, and assures that substantially all of the production fluid is displaced from the filling chamber prior to shutting off the supply pressure fluid. Furthermore the present invention provides a definite means of determining exactly how much residue pressure is present in the filling chamber before the valve reopens to the discharge of motive pressure fluid. This is accomplished by having a definite amount of weight imposed against an orifice when the pressure down is no longer sufficient to hold the weight of the flange 91 holding the valve 47 away from its seat. The flange 91 and valve 47 are allowed to drop under gravity of their own weight and are not hindered by any particles of sand that may be present in the residue fluid, or any mechanical hindrances such as springs or the like. The present invention is capable of being utilized in wells having a high sand pressure maintaining a high fluid level in the well bore, and is also very adaptable to oil wells where only a minimum of

11

fluid is present at the bottom of the bore in what are commonly known as "stripper" wells providing a low fluid level. In the latter adaptation the only production pressure necessary would be an amount necessary to move the ball valve 65 off its seat allowing the flow of well liquid into the displacement chambers against whatever small amount of residue pressure may be present in the displacement chambers.

Changes may be made in the combination and arrangement of parts as heretofore set forth in the specification and shown in the drawings, it being understood that any modification in the precise embodiment of the invention may be made within the scope of the following claims without departing from the spirit of the invention.

In the claims:

1. In an apparatus for lifting fluid from a well comprising an automatic valve unit communicating with an inlet passageway having constantly maintained motive pressure fluid therein, and a filling chamber for well fluid emitting from the production strata, a reservoir communicating with the valve unit and the filling chamber, said valve unit comprising a valve mechanism movable by motive pressure fluid to one position for directing motive pressure fluid to the filling chamber, and movable to another position preventing discharge of motive pressure fluid to the filling chamber and simultaneously permitting an exhaust of residue motive fluid therefrom, and means in the valve mechanism directly responsive to the motive pressure fluid for maintaining the valve mechanism in the first mentioned position, a piston unit movable in response to motive pressure fluid and operably connected with the above mentioned means to cause a movement thereof permitting the valve mechanism to be moved to the position allowing exhaust of residue motive fluid from the filling chamber, and means independent of the valve mechanism and responsive to the hydrostatic head of well fluid in the reservoir for introducing motive pressure fluid thereto for slugging the well fluid to the top of the well.

2. In an apparatus for lifting fluid in a well comprising an automatic valve mechanism communicating with an inlet passageway having constantly maintained motive pressure fluid therein, a filling chamber for well fluid emitting from the production strata, a piston movable in response to motive pressure fluid into operable connection with the valve mechanism, said piston moving against previously displaced well fluid to provide a snubbing action for the piston until substantially all of the production fluid is displaced from the filling chamber, means in the valve mechanism responsive to the movement of the piston permitting movement of the valve mechanism to a position for exhausting residue motive fluid from the filling chamber, said means maintained in said position by the pressure of the residue motive fluid after displacement of the well fluid until there is substantially complete exhaust of the residue fluid from the apparatus.

3. In an apparatus for lifting fluid in a well comprising an automatic valve mechanism communicating with an inlet passageway having constantly maintained motive pressure fluid therein, a filling chamber for the well fluid emitting from the production strata, a piston movable in response to motive pressure fluid into operable connection with the valve mechanism, said piston moving against the previously displaced well fluid

providing a snubbing action for the piston until substantially all of the production fluid is displaced from the filling chamber, a pilot valve in the valve mechanism controlling the movement thereof, a valve controlling the movement of the pilot valve, said last mentioned valve responsive to the movement of the piston to cause movement of the pilot valve to a position permitting exhaust of residue motive fluid from the filling chamber, said valve maintained in said last mentioned position by the pressure of the residue motive fluid after displacement of the well fluid until there is a substantially complete exhaust of the residue fluid from the filling chamber whereby said valve is permitted to move to its original position by gravity.

4. In an apparatus for lifting fluid from a well comprising an automatic valve mechanism communicating with an inlet passageway having constantly maintained motive pressure fluid therein, a filling chamber for the well fluid emitting from the production strata, a piston movable in response to motive pressure fluid into operable connection with the valve mechanism, said piston moving against the previously displaced well fluid providing a snubbing action for the piston until substantially all of the production fluid is displaced from the filling chamber, a pilot valve in the valve mechanism controlling the movement thereof, a valve controlling the movement of the pilot valve, said last mentioned valve responsive to the movement of the piston to cause movement of the pilot valve to a position permitting exhaust of residue motive fluid from the filling chamber, said valve maintained in said last mentioned position by the pressure of the residue motive fluid after displacement of the well fluid until there is a substantially complete exhaust of the residue fluid from the filling chamber whereby said valve is permitted to move to its original position by gravity, and an independent valve unit comprising a series of vertically spaced valves in communication and responsive to the hydrostatic head of well fluid in the reservoir for introducing motive pressure fluid into the reservoir for slugging the well fluid to the top of the well.

5. In an apparatus for lifting fluid in a well including a filling chamber, a valve unit for controlling the introduction for constantly maintained motive pressure fluid into the filling chamber for displacing oil emitting thereto from the production strata, a reservoir for receiving the displaced fluid, said valve unit comprising an elongated valve movable in one position to permit discharge of motive pressure fluid to the filling chamber, and movable in another position to prevent discharge of motive pressure fluid to the chamber and simultaneously permitting exhaust of residue motive fluid from the chamber, a pilot valve slidably disposed in the elongated valve for controlling the flow of motive pressure fluid causing movement of said elongated valve to said first mentioned position, a polygonal valve disposed in the pilot valve for controlling the movement thereof, a lower piston unit operably connected with the polygonal valve and responsive to motive pressure fluid to cause an unseating of said polygonal valve and permitting an exhaust of the motive pressure fluid from one side of said elongated valve to permit a movement of said elongated valve into position for exhausting residue motive fluid from the filling chamber, said polygonal valve adapted to remain in said unseating position by the pressure of the residue fluid until a substantially

complete exhaust of the residue motive fluid whereby the polygonal valve is moved by gravity to a seating position.

6. In an apparatus for lifting fluid in a well including a filling chamber, a valve unit for controlling the introduction for constantly maintained motive pressure fluid into the filling chamber for displacing oil emitting thereto from the production strata, a reservoir for receiving the displaced fluid, said valve unit comprising an elongated valve movable in one position to permit discharge of motive pressure fluid to the filling chamber, and movable in another position to prevent discharge of motive pressure fluid to the chamber and simultaneously permitting exhaust of residue motive fluid from the chamber, a pilot valve slidably disposed in the elongated valve for controlling the flow of motive pressure fluid causing movement of the elongated valve to said first mentioned position, an aperture in the pilot valve in communication with the exhaust passageway, a polygonal valve disposed in the pilot valve and movable on and away from the aperture to control movement of the pilot valve, a piston unit operably connected with the polygonal valve and responsive to motive pressure fluid to cause an unseating of the polygonal valve from the aperture and permitting an exhaust of the motive pressure fluid from one side of said elongated valve to permit movement of said valve into a position for exhausting of residue motive fluid from the filling chamber, said polygonal valve adapted to remain away from said aperture until a substantially complete exhaust of the residue motive fluid from the filling chamber to permit the valve to move by gravity to a seating position against the aperture.

7. In an apparatus for lifting fluid from a well having an eduction tubing and a well casing, said apparatus including a reservoir communicating with the eduction tubing, a filling chamber communicating with the well casing and the reservoir, an automatic valve mechanism operable in one position to direct constantly maintained motive pressure fluid into the filling chamber for displacing well fluid therefrom, said mechanism operable in another position to bleed off residue motive pressure fluid after displacement of well fluid from the filling chamber, means for retarding the movement of the mechanism to the last mentioned position until substantially all the well fluid is displaced from the filling chamber, and means in the valve mechanism maintained in said last mentioned position by the pressure of the residue motive fluid until a substantially complete exhaust of the residue motive fluid from the apparatus, and means independent of the valve mechanism and responsive to the hydrostatic head of well fluid in the reservoir for introducing motive pressure fluid thereto to slug the well fluid to the top of the well.

8. In an apparatus for lifting fluid from a well having an eduction tubing and a well casing, said apparatus including a reservoir communicating with the eduction tubing, a filling chamber communicating with the well casing and the reservoir, an automatic valve mechanism operable in one position to direct constantly maintained motive pressure fluid into the filling chamber for

displacing well fluid therefrom, said mechanism operable in another position to bleed off residue motive pressure fluid after displacement of well fluid from the filling chamber, and an independent intermittent valve mechanism comprising an elongated valve having upper and lower seating members in communication with the motive pressure fluid, a piston valve extending from the lower seating member in vertical spaced relation thereto, said elongated valve and piston valve responsive to the hydrostatic head of fluid in the reservoir to move said lower seating member to a position permitting discharge of motive pressure fluid to the reservoir for slugging the well fluid to the top of the well.

9. In an apparatus for lifting fluid from a well having an eduction tubing and a well casing including a reservoir communicating with the eduction tubing, a filling chamber communicating with the well casing and the reservoir, an automatic valve mechanism operable in one position to direct constantly maintained motive pressure fluid into the filling chamber for displacing well fluid therefrom, said mechanism operable in another position to bleed off residue motive pressure fluid after displacement of well fluid from the filling chamber, a tripping mechanism operably connected with the valve mechanism for controlling the positioning thereof, said tripping mechanism maintained in one position by the residue pressure fluid during the exhausting thereof to maintain the valve mechanism in said last mentioned position, said tripping mechanism adapted to be moved by gravity to another position with a substantial exhaust of the residue pressure fluid whereby said valve mechanism is permitted to move to the said first mentioned position.

10. In an apparatus for lifting fluid from a well having an eduction tubing and a well casing including a reservoir communicating with the eduction tubing, a filling chamber communicating with the well casing and the reservoir, an automatic valve mechanism operable in one position to direct constantly maintained motive pressure fluid into the filling chamber for displacing well fluid therefrom, said mechanism operable in another position to bleed off residue motive pressure fluid after displacement of well fluid from the filling chamber, means operably connected with the valve mechanism for controlling the positioning thereof, said means maintained in one position by the residue pressure fluid during the exhausting thereof to maintain the valve mechanism in said last mentioned position, said means adapted to be moved by gravity to another position with a substantial exhaust of the residue pressure fluid whereby said valve mechanism is permitted to move to the said first mentioned position.
